(57) **CLAIM**

The ornamental design for packaging for jewelry, as shown and described.

DESCRIPTION

FIG. 1 is a front perspective view of our new design for packaging for jewelry;

FIG. 2 is a back perspective view of FIG. 1;

FIG. 3 is a front view of FIG. 1;

FIG. 4 is a back view of FIG. 1;

FIG. 5 is a left side view of FIG. 1;

FIG. 6 is a right side view of FIG. 1;

FIG. 7 is a top view of FIG. 1; and,

FIG. 8 is a bottom view of FIG. 1.

The broken lines depict portions of the packaging for jewelry that do not form part of the claimed design.
